UNITED STATES PATENT OFFICE.

JOHN CHARLES PUGH, OF LONDON, ENGLAND, ASSIGNOR OF ONE-HALF TO WHITE-HEAD, MORRIS & COMPANY, LIMITED, OF LONDON, ENGLAND.

INKING MECHANISM FOR PRINTING-MACHINES.

1,243,341.

Specification of Letters Patent. Patented Oct. 16, 1917.

Application filed April 14, 1917. Serial No. 162,082.

To all whom it may concern:

Be it known that I, JOHN CHARLES PUGH, a subject of the King of Great Britain, residing at Whitehead, Morris & Company 5 Limited's Printing Works, Tower Hill, London, England, have invented new and useful Improvements in Inking Mechanism for Printing-Machines, of which the following is specification.

10 This invention relates to inking mechanism for letter-press printing machines and has for its object to provide means whereby fluid ink, such as ordinary writing ink, may be applied to a printing surface, as described, for instance, in the specification of 15 British Letters Patent No. 1044, A. D. 1914.

In practice the use in a letterpress printing machine of fluid ink, that is to say, an ink such as ordinary writing ink, to which 20 no thickening has been added, has heretofore been considered almost impossible owing to the difficulty of applying sufficient ink to produce a good impression without at the same time supplying an excess of ink. As 25 the result of numerous experiments, I have discovered that if I employ in conjunction with an ink fountain or trough a pair of accurately contacting rollers which are driven at a constant and uniform speed, one 30 of which dips into the ink, while the other serves as a regulating supply roller, and if, in addition, I employ a vibrator roller for transferring the ink from the operating roller directly to an inking bed, such vibrator 35 roller being covered with an absorbent material, a most even distribution of ink can be obtained, and this invention, therefore, consists in such an arrangement.

In the accompanying drawing—

40 Figure 1 is a front view showing the inking mechanism in connection with so much of a printing machine as is necessary to illustrate the invention, and

Fig. 2 is a side elevation of the same.

45 In these figures *a* indicates the framing of the printing machine and *b* an inking slab from which the ink is conveyed to the printing surface in the ordinary manner.

The inking mechanism comprises two 50 rollers *c*, *d* carried on shafts *c*¹, *d*¹ mounted in brackets *e*, *e* on the frame. The roller *c*, which I term the "fount" roller, is arranged over a trough *f* of porcelain or other material which will not be injured in any way 55 by the ink or cause injury to the latter, the

said roller being arranged so that, as it rotates, it will dip into the ink and be wetted thereby. The roller *d*, which I term the regulating supply roller, runs in contact with the roller *c*, the shafts of the two rollers 60 being geared together, for instance, as indicated at *g*, *g* to move in unison and constantly driven, so that the ink which the fount roller takes up from the trough *f* will be evenly applied to the regulating 65 supply roller *d*. In order to provide for adjusting the pressure between the two rollers and consequently also the feed, I make the bearings *h*, *h* in which the shaft *d*¹ is carried, adjustable, for instance, by means of 70 screws *i*, *i* whereby very accurate adjustment can be obtained.

In connection with the regulating supply roller *d* I arrange what is termed a "vibrator" that is to say, a roller *k* mounted in 75 bearings upon oscillating arms *l*, *l* the movement of which is controlled by a cam or other device, not shown, in such a manner that the said vibrator is alternately moved from the position indicated in the dotted 80 lines in Fig. 2, in which it is in contact with the regulating supply roller *d*, to a position indicated in full lines in the said Fig. 1, in which it will come into contact with the inking slab *b* as the latter reciprocates beneath it, and transfer ink to it. This inking slab is preferably composed of glass or other material which will not act injuriously upon the ink and travels beneath the said vibrator and also beneath waver rollers, 85 not shown, by means of which the ink is distributed and then conveyed to the printing surface.

In practice the fount roller *c* and regulating supply roller *d* are preferably composed 95 of hard rubber, or faced with hard rubber, while the vibrator *k* is faced with absorbent material such as felt or a smooth surfaced woven fabric. The waver rollers are preferably composed of printers' roller composition cased in rubber, although for some classes of work printing is greatly improved by the employment of absorbent waver rollers.

The improved printing mechanism is particularly suitable for printing checks for the prevention of fraud.

Claim:

Inking mechanism for letterpress printing machines using fluid ink, such as ordinary 110

writing ink, comprising a fountain roller and a regulating supply roller running in accurate contact with one another and which are constantly and uniformly driven, a trough for containing ink into which the fountain roller will dip, an inking bed, a vibrator roller for transferring ink from the regulating roller to the inking bed and

a covering of absorbent material upon the said vibrator roller, substantially as described.

JOHN CHARLES PUGH.
